Joseph S. Jones,
Letters Patent, No.

The Subject referred to in these Letters Patent, making part of the same,
containing a description in the words of the said Joseph S. Jones, hereto,
of his Improvement, being a Recipe for making permanent "Yellow"
"Tawne, or Buff" Colors.

Method of preparing the Cloth or Stuffs for coloring. — Boil the Cloth
in the bleached Brownstock, or the ingredients for washing the Cloth in
the manufacturer's Thread or musk state, and having washed it well in hot
water and with common brown soap, rinse it well with hot water and let
it stand in it over night; in the morning take it out and let it stand dry in
the shade, it is then fit for coloring.

To make coloring matter for one hundred
pieces Yellow or Buff Tawneas, of seven yards in length. Boil in a copper
Boiler, with fifty gallons Spring water, 3 lbs. Gunpowder, and 3 lbs. Sulphur
(in a linen bag) and let them boil for six hours, and in another boiler
with fifty gallons Spring water, boil in a bag, 3 lbs. Sulphur, and 3 lbs.
Balsam, which boil for the space of six hours also. When done
take the Liquids from both Boilers and mix them together and let them stand
till the water is cold, then dye your Cloth or stuff in it for the space of ten
minutes. Then take them out and wash them in cool water, very
weak, of the Sulphuric acid, from which take the Cloth or stuff, and wash
them through clear Spring water and let them stand, and let them dry
in the shade. An addition of Sulphur and a little acid turns the colors
more yellow, and the addition of King's more red. — If you like it not the
size of the last possible quantity. — The adding of a little common soap
to the coloring matter, will give a grayish appearance to the goods. The
Colors produced by this Solution, will be fast and immovable to
Water, or soap, and may quickly be turned undoubtly.

To make the yellow or Buff Tawneas
for sample and for the Department of the Cloth of my factory, I dyed by
